BERTHOLD MENKEL, OF COLOGNE, GERMANY.

DISPLAY CASE.

Application filed June 8, 1926, Serial No. 114,565, and in Germany June 16, 1925.

The invention relates to improvements in display cases for advertising or other purposes, its objects being to provide display chambers for insertion in such cases in the 5 usual manner, which however are adjustable in size to suit all requirements, and are readily dismountable for transport.

With these objects in view the invention provides a display chamber comprising a 10 rear wall and side walls extending forwardly therefrom, said walls being constructed from frames built up of interengaging side and corner pieces on which the canvas or the like to be displayed is stretched. Preferably 15 the frame pieces are each provided with squared dowel pins at one end and a corresponding hole in the other end, whereby they may be readily assembled or dismembered. The frames are simply connected at their 20 abutting edges. It is evident that in this manner the frames can be prepared at the factory of standard dimensions and can be supplied directly for any size of show case, can be very readily transported and fitted 25 up on the spot. Further they may be readily taken to pieces or made into a different size as desired.

In the accompanying drawing illustrating the invention, Figure 1 shows the device in 30 front perspective view and Fig. 2 in plan. Fig. 3 shows one of the stretching frames in front elevation, Fig. 4 shows same in vertical cross-section, and Figs. 5 and 6 show the frame members in detail to an enlarged scale. 35 The display chamber proper is partitioned off from the show case or display window *a* which is closed at the front by a window 1, by a background 3 and two side walls 4. The background 3 and walls 4 are stood on the 40 floor 2 of the show case and consist of light frames on which is stretched material serving for decoration, the vertical abutting edges being provided with simple devices by means of which they can be connected so as to be 45 readily detachable. For example, for this purpose, eyes 5 may be mounted at the top and bottom of each adjacent vertical member of the frames, so that they can be connected by means of wire or thread. The side walls 50 4, 4 may be braced together by one or more rods, stays or wires 12 (Figure 2). These rods may be placed at the top or bottom of the side walls or both.

The frame members 6, advantageously 55 consisting of wood, support the edges of the

display sheets 7 bearing decorative or advertising matter by means of broad headed pins, drawing pins or the like in known manner so that they can be readily detached without damage, and with advantage are made up of 60 pieces 8 detachably connected together and secured at the corners by angle pieces 9. Each of the pieces 8, 9, is provided at one end with a rectangular dowel pin 10 and at the other end with a hole 11 of exactly corresponding dimensions into which the dowel pin of the adjacent piece can be snugly fitted. The rectangular form of the pins 10 and holes 11 prevents relative rotation of the 65 frame pieces.

By the assembly of the frames of such pieces economical manufacture in the production of the frames is extraordinarily facilitated. As is readily seen from four angle pieces and convenient numbers of frame 70 pieces of two or three different lengths, it is possible to make very quickly stretching frames of different size, and thus to prepare for any show case to be fitted, suitable rear and side walls, which afford the desired 75 enclosed display space by merely connecting their rear abutting edges.

I claim:—

1. An adjustable display chamber for show cases comprising in combination rear and 80 side frames formed of interchangeable interfitting sections, said frames consisting of corner and side pieces having interchangeable interfitting squared dowel connection, display sheets detachably mounted on said 85 frames, means for detachably securing said frames at adjacent edges and means for bracing said frames together.

2. An adjustable display chamber for show cases comprising in combination rear and 90 side frames formed of interchangeable interfitting section, said frames consisting of corner and side pieces having interchangeable interfitting squared dowel connection, said 95 corner and side pieces each having a squared pin at one end and a corresponding squared hole at the other end, the pin at the end of one piece being adapted to fit into the hole in the end of the adjacent piece, display sheets detachably mounted on said frames, means 100 for detachably securing said frames at adjacent edges and means for bracing said frames together.

BERTHOLD MENKEL.
